POWER OPERATED KNIFE HANDLE

Arnold O. Wolf, Racine, Wis., assignor to Scovill Manufacturing Company, Waterbury, Conn., a corporation of Connecticut

Continuation of design applications Ser. No. 85,400 and Ser. No. 85,401, May 21, 1965. This application Oct. 6, 1965, Ser. No. 87,526

Term of patent 14 years

(Cl. D22—3)

Fig. 1

Fig. 2

Fig. 3

Fig. 4

Fig. 5

Fig. 6

Fig. 7

Fig. 8

Fig. 9

Fig. 10

FIG. 1 is an elevational side view of a power operated knife handle showing my new design wherein the corners of the grip portion are rounded.

FIG. 2 is a top plan view thereof.

FIG. 3 is a bottom view thereof.

FIG. 4 is an elevational end view thereof as seen from the left; and

FIG. 5 is an elevational end view thereof as seen from the right.

FIG. 6 is an elevational side view of a power operated knife handle of a modified form wherein the corners of the grip portion are angular.

FIG. 7 is a top plan view thereof.

FIG. 8 is a bottom view thereof.

FIG. 9 is an elevational end view thereof as seen from the left; and

FIG. 10 is an elevational end view thereof as seen from the right.

The fragmentary broken line showing of the knife blade

in FIGS. 1, 2, 3, 6, 7 and 8 is for illustrative purposes only.

This application is a continuation of my copending applications Serial Nos. D. 85,400 and D. 85,401 filed on May 21, 1965, and now abandoned.

I claim:

The ornamental design for a power operated knife handle, substantially as shown and described.
